UNITED STATES PATENT OFFICE

1,985,799

OIL BURNER

Frederick W. Scheifle, Audubon, N. J.

Application April 23, 1932, Serial No. 607,141

5 Claims. (Cl. 158—28)

This invention relates to improvements in oil heating systems and pertains particularly to an automatically controlled heating system.

The primary object of the present invention is to provide an oil burner having a high and low operating pressure, the low operating pressure being employed in the starting of the heater to prevent the back-flow of oil gases from the chimney stack when the stack is cold.

Another object of the invention is to provide an oil burner having a high and a low operating pressure and a thermostatically controlled smoke stack switch which operates after the stack has become heated to an increased degree to cause the oil to flow into the heater under high pressure in place of the low pressure at which it was started.

A still further object of the invention is to provide an oil burner structure which is designed to inject air with atomized oil in such a manner as to practically eliminate noise and also spread the burning oil jet so as to effect an even distribution of the heat therefrom over the walls of the heater into which it is projected.

Other objects and advantages of the invention will become apparent as the description of the same proceeds and the invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in top plan of the oil burner structure embodying the present invention;

Figure 2 is a view in rear elevation of the same;

Figure 3 is a view in side elevation of the burner showing the same connected with a heater such as a furnace boiler or the like and also showing the smoke stack control switch connection with the burner;

Figure 4 is a horizontal sectional view taken substantially upon the line 4—4 of Figure 3;

Figure 5 is a sectional view taken substantially upon the line 5—5 of Figure 4;

Figure 6 is a schematic view of the pipe system and valves associated with the oil burner;

Figure 7 is a diagram of the electrical system associated with the burner;

Figure 8 is an enlarged longitudinal sectional view of the burner atomizing or spraying nozzle; Figure 9 is a detail vertical sectional view through the smoke stack or flue switch; Figure 10 is a view in front elevation of the switch from which the usual cover has been removed; Figure 11 is a horizontal sectional view through the low pressure valve, showing diagrammatically the construction thereof.

Referring now more particularly to the drawings wherein like numerals of reference indicate corresponding parts throughout the several views, the numeral 1 indicates generally a heater of any suitable type, with which the heating device embodying the present invention is shown connected, which heating device is indicated generally by the numeral 2. The fire-box entrance for the heater or boiler 1 is indicated by the numeral 3 and the chimney or flue connection therefor is indicated by the numeral 4.

The heating element embodying the present invention and which is indicated by the numeral 2 comprises a pair of blowers, each of which is indicated by the numeral 5 and which has the axial air inlet openings 6 and the tangential outlet 7 which opens into an air passageway or conduit 8. These air conduits converge and are joined at their ends to form a single relatively large discharge mouth or opening 9 which fits the door opening 3 leading into the heater or boiler 1, as shown in Figure 4.

At each side of the mouth 9 of the air passageway are formed the plurality of inwardly projecting fingers 10. These fingers at each side of the opening are divided into two groups, the fingers of each group being in vertically spaced

relation and the fingers of one group being in the planes of the passageways between the fingers of the other group, and one group of fingers is slightly in advance of the other so that air passing along the adjacent conduit and reaching the mouth 9 of the air passageway into the heater or boiler will first pass through the openings between one group of fingers and impinge against the fingers of the group therebehind and will flow downwardly to pass between the openings or passageways between this second group of fingers.

The air will thus enter the door opening of the heater or boiler in a series of vertically spaced sheets. As a result of the manner in which the air is distributed by these fingers at opposite sides of the conduits 8 the proper amount of air is concentrated about the spray of oil which is delivered into the boiler, by the apparatus about

to be described, to effect the proper combustion thereof.

5   Mounted upon a suitable support upon the blower casings 5 is an electric motor 11, the armature shaft of which has an extension shaft 12 connected with each end, each of which extension shafts passes through a fan housing 5 and has the fan blades 13 mounted thereon in a housing. Upon the outer end of each shaft 12 a draft 10 control plate 14 is mounted which may be moved on the shaft relative to the air inlet opening 6 to regulate the amount of air drawn into the blower.

Upon one of the shafts 12 there is mounted a pulley wheel 15 and beneath this pulley wheel is located a liquid pump 16 which may be of any suitable type, such for example, as a gear pump. This pump 16 has an operating pulley 17 which is connected with the pulley 15 by the belt 18.

20 The numeral 19 indicates a strainer of a suitable type for straining fuel oil, to which leads a pipe 20 which is connected with a suitable oil storage tank and this strainer is connected by the pipe 21 with one side of the pump 16. The outlet side of the pump 16 is connected by the pipe 22 with a high pressure bypass and cut-off valve unit 23 of a suitable standard make and the low pressure outlet side of this valve is connected by the pipe 24 with the inlet 25 of a second bypass and cut-off valve unit 26 which operates or opens at a lower pressure than the valves in the valve unit 23. Between the valve units 23 and 26 the connecting line 24 has inserted therein a magnetically operated valve 27.

35 The high pressure valve unit 23 may be set to open at a pressure of approximately one hundred pounds and when it opens under this pressure oil flows therefrom through the pipe line 28 to the spray nozzle 29 which is located in the outlet 40 9 at the convergent ends of the air passageways 8, so as to discharge oil directly into the heater or boiler 1. This nozzle 29 is preferably of a whirling spray type.

45 The fuel feed valve in the low pressure valve unit 26 may be set to operate or open at a pressure of approximately fifty pounds and when it opens at this pressure oil will flow therethrough through the pipe line 30 into the pipe line 28 through the coupling 31 and then to the spray nozzle, as will be readily apparent from an examination of the drawings.

Suitable return flow pipes 32 are connected with the pressure valve units 23 and 26 through the pressure operated by-pass valves 26^a to return excess oil to the storage reservoir. Figure 11 represents diagrammatically a low pressure valve unit of the type indicated at 26. This valve unit has therein the two spring controlled small valves 26^a and 26^b which control the flow of fluid from the central chamber 26^c into the end chambers, the inlet to the central chamber 26^c being indicated by the numeral 25. The end of the outlet pipe 30 which leads to the pipe 44 and nozzle 29 is connected with the end of the valve structure 26 which leads into the chamber 30^a which is adjacent the valve 26^b and a ball check 30^b is placed at the outlet of the chamber 30^a to prevent back pressure from the pipe 30 into this chamber. At the opposite end of the valve structure 26 is the chamber 32^a from which leads the by-pass pipe 32. In this valve 26 the tension of the spring controlling the valve element 26^b is adjusted so that the valve element will unseat when the pressure in the chamber 26^c reaches approximately fifty pounds or whatever other

low pressure may be selected for the operation of the by-pass valve and the spring controlling the valve element 26^a may also be adjusted for tension so that this element will unseat at a slightly greater pressure than the element 26^b so that the delivery of fuel through the pipe 30 will be maintained at a substantially constant pressure.

The by-pass valve unit 23 is of the same construction as the valve unit 26 with the exception of the fact that the check valve 30^b is not used in the outlet opening leading to the pipe 28. The valve unit 23 has an additional pipe coupled therewith which is the pipe 22 which leads from the pump into the center chamber between the elements which in the valve 26 are indicated by the numerals 26^a and 26^b. In the valve 26 the opening corresponding with that through which the pipe 22 discharges in the valve 23 is closed.

In Figure 7 there is shown the wiring diagram for the heater unit. In the operation of the heater unit a suitable thermostat 33 is employed in a room of the building which is heated by the heating system and one side of this thermostat is connected with one side of a current supply circuit by the wire 34, while the other side of the thermostat is connected by a wire 35 with a terminal 36 of a junction box. To this terminal 36 is connected one end of a wire 37 which leads to the motor 11 and the return from the motor is connected with a terminal 38 of the junction box through the medium of the wires 39 and 40. The terminal 38 of the junction box is connected by the wire 41 with the other side of the current supply line.

Connected in series between the terminal 36 of the junction box and the wire 39 which leads to the terminal 38 thereof are the magnetic valve 27 and a temperature responsive switch 42 which is installed in the stack 4 of the heating boiler. From this diagram it will be apparent that when the thermostat 33 operates to close the electric contacts therein due to the reduction in the temperature of the surrounding atmosphere below a predetermined point, the motor 11 will be set in operation and will start the pump 16 to building up a pressure of oil in the pipes 22 and 24. The magnetic valve 27 is open when energized. Since the oil flow control valve 26^b in the valve unit 26 is set to open at a lower pressure than the corresponding valve in the valve unit 23 it will be apparent that oil will be pumped through the magnetic valve 27 and through the pressure valve 26^b to the spray nozzle 29 by way of the pipes 30 and 28. Ignition of the oil spray at the nozzle 29 is accomplished through a gas pilot 43 which is located adjacent the nozzle 29 and which remains burning at all times.

The oil burning under low pressure at the nozzle 29 will gradually heat up the boiler and the flue or stack 4 and thus the starting of the heating system will be effected without oil gases being forced back into the room in which the heater is installed, as would be the case if the device started at once under high pressure while the boiler and smoke stack are cool. 60 65

After the smoke stack has become heated to an increased temperature, the heat responsive switch 42 will be opened, thus breaking the circuit to magnetic valve 27 as will be readily apparent upon reference to the circuit diagram, and shut-off the flow of oil to the low pressure operated valve unit 26. The oil pressure in the pipe 22 will then be built up by the pump to the point where the pressure operated feed valve in the valve unit 23 is 75

forced to open and the oil will then be discharged through this valve and through the pipe line 28 through the nozzle 29 under relatively high pressure.

5 Due to the provision of the spaced finger members 10 in the opening 9 at the door to the boiler or heater, the air forced into the heater by the fans 5 will enter in strata or sheets so that the burning oil mixing therewith will be spread evenly over the interior of the boiler and also the burning of the oil will be effected with a minimum of noise.

10 In Figure 8 there is shown an enlarged longitudinal sectional view of the atomizing nozzle 29 which is of a standard construction and comprises a sleeve portion 43 which threads onto the oil supply pipe 44 leading from the branches 28 and 30 and in the forward end of this sleeve there is threadably mounted the removable tip 45 having the relatively small outlet opening 46. Within the sleeve 43 is a gauze screen 47 and in the tip is located a fluted element 48 about which the oil flows and which operates to break up and thoroughly atomize the same.

15 Figures 9 and 10 show the flue operated switch 42 in enlarged detail. This switch is also of a standard construction and comprises an oscillatable shaft 49 on which is mounted the heat sensitive element 50 which when subjected to heat causes the shaft 49 to rotate so as to oscillate the mercury tube 51 and thus close the circuit in which the device is located. As this switch is of a standard make, as previously stated, further detailed description thereof is unnecessary.

20 25 In the operation of the present burner the fuel feed valves in the valve units 23 and 26 are set so that the elements controlling the flow of fluid therethrough to the pipes 28 and 30 will unseat at the desired pressures and the elements therein which control the by-passing of the fluid back to the reservoir are correspondingly adjusted. The motor 11 is set into operation thereby simultaneously starting the fans 5 and the oil pump 16. The magnetic valve 27 is open and since the by-pass valve in the valve unit 23 is set to open at a higher pressure than the corresponding valve in the valve unit 26, the oil will be pumped through the pipe 22 into the central chamber of the valve unit 23 and will flow from this central chamber through pipe 24 and the inlet 25 of the low pressure valve unit 26 into the chamber 26c thereof. When the pressure is built up in this latter chamber to approximately fifty pounds the valve 26b will be unseated and the oil will flow through the pipes 30 and 44 to the nozzle 29 from which it will be ejected as a spray into the boiler 1. The air delivered through the conduits 8 into the boiler is maintained at a constant pressure and due to the effect of the distributor fingers 10 a part thereof will be directed in the proper manner toward the nozzle so as to supply the correct amount for the combustion of the oil entering the boiler. The remainder of the air will be discharged into the boiler further in advance of that delivered directly to the nozzle. After a period of operation of the burner with the oil being delivered at low pressure, the boiler and smoke stack will become heated to the point where the thermostat 50 will be operated so as to actuate the magnetic valve 27, to the closed position. This will result in the closing off of the flow of oil through the cross-over pipe 24 between the units and the pressure will immediately build up in the valve unit 23 to the point where the valve 26b therein will be opened to discharge oil into the pipe line 28 and

from there to the pipe 44 and the nozzle 29. By the proper adjustment of the valve element 26a in the valve unit 26 and the corresponding element in the valve unit 23 any material increase in oil pressure in these valves over the pressure required to open the same for the discharge of oil into the pipes 28 and 30, will result in the passing of some of the oil back through the pipes 32 to the reservoir.

25 With the air being delivered at a constant pressure during the operation of both the low and high pressure valves the combustion of the oil at the start, when the low pressure valve is open, is not the most efficient but this operation does not continue for any material length of time before the stack becomes sufficiently heated to effect the shut-off of the low pressure valve and the turning on of the high pressure valve. The air supply will then be properly proportioned with the amount of oil being delivered under high pressure to give the most efficient results.

30 By adjusting the positions of the plates 14 the quantity of air delivered to the combustion chamber by the fans may be readily controlled to properly proportion it to the quantity of oil introduced into the boiler under high pressure.

35 Having thus described the invention, what is claimed is:—

1. In a liquid fuel heater structure of the character described, a combustion chamber having a gas exhaust flue and an inlet opening, a fuel injector nozzle arranged to discharge through the inlet opening into the combustion chamber, a pair of fuel conducting pipes leading to said injector, a combined pressure responsive and by-pass valve unit controlling one of said pipes and designed to open at a relatively low pressure, a second combined pressure responsive and by-pass valve unit in the other of said pipes and set to open at a high pressure, means for pumping fuel from a source of supply to both of said valve units, an electro-magnetically controlled valve governing the flow of fuel to the low pressure valve unit, and a heat responsive means disposed in the gas exhaust flue and coupled with said electro-magnetic valve to close the same at an increased flue temperature.

2. In a liquid fuel feeding system having a fuel injector arranged to deliver fuel under pressure to a combustion chamber, a pressure fuel feeding means, means for delivering fuel at different pressures from said feeding means to said injector, said last means including a pair of valve units, each unit having pressure actuated fuel feed and by-pass valves therein, said fuel feed valves being connected in parallel with said injector, and a valve controlling the flow of fuel to one of said units.

3. In a liquid fuel burning structure, a combustion chamber, a flue leading therefrom, a fuel nozzle discharging into said chamber, a pair of liquid fuel lines communicating with said nozzle, high pressure operated fuel feed and by-pass valves controlling one line, low pressure operated fuel feed and by-pass valves controlling the other line, a fuel transfer line connecting each of said lines at a point intermediate said fuel feed and by-pass valves, means for delivering fuel under pressure to said one line at a point intermediate said fuel feed and by-pass valves, means controlled by said by-pass valves communicating with the source of fuel, means in said transfer line for closing the same, and means actuated by an increased temperature in said flue after a predetermined period of operation of the burner with fuel

passing through the low pressure feed valve, to operate the means in said transfer line to close the same.

4. In a liquid fuel burning structure, including a combustion chamber having a gas lead-off flue, a fuel spray nozzle disposed in said chamber, a pair of fuel lines communicating with said nozzle, pressure actuated fuel feed and by-pass valves controlling each of said lines, one of said fuel feed valves being set to open at a lower pressure than the other, a fuel transfer line connecting said lines at points intermediate said fuel and by-pass valves; an electromagnetically operated valve in said transfer line, means for discharging fuel under pressure into the transfer line between the magnetic valve and the fuel feed valve which is set to open at the highest pressure, and a thermostatically operated switch disposed in said flue and connected with said magnetic valve whereby the latter valve will be shut at a predetermined fuel temperature.

5. In a liquid fuel burner, a burner nozzle, a control unit comprising a shell having a central inlet and outlet and two remote outlets, a pair

of pressure actuated valves in the shell each controlling passage of fluid from the inlet to a remote outlet, one of said valves being connected with a pipe communicating with said nozzle and constituting a fuel feed valve and the other valve constituting a by-pass valve, a second control unit comprising a shell having a central inlet and two remote outlets, a pair of pressure actuated valves in the second unit shell each controlling passage of fluid from the inlet to an outlet thereof, one of said valves of the second unit shell being connected with another pipe communicating with said nozzle and constituting a fuel feed valve and the other valve of the second unit constituting a by-pass valve, the fuel feed valve of the first unit being set to open at a higher pressure than the fuel feed valve in the second unit, a pipe coupling the center outlet of the first unit shell with the inlet of the second unit shell, a valve in said last pipe, fuel supply means for injecting fuel fluid under pressure into the inlet of the first unit shell, and pipes connecting said by-pass valves with said fuel supply means.

FREDERICK W. SCHEIFELE.
